UNITED STATES PATENT OFFICE.

VOJTECH PUC, OF PRAGUE-VINOHRADY, BOHEMIA.

SNAP BUTTON.

1,415,474.

Specification of Letters Patent.

Patented May 9, 1922.

Application filed August 6, 1919. Serial No. 315,618.

To all whom it may concern:

Be it known that I, VOJTECH PUC, a citizen of the Czechoslovak Republic, residing at Prague-Vinohrady, in Bohemia, have invented certain new and useful Improvements in Snap Buttons, of which the following is a specification.

This invention relates to separable fasteners of the kind generally known as press buttons or snap buttons, and which are composed of two members, a stud member and a socket member, which latter carries springs which engage the stud when the latter is in the socket.

Ordinarily the two members of the fastener are connected to the garment by means of threads extending through what are termed thread holes in the base plates of the members, but according to my invention wire is employed for this purpose.

My improvements are illustrated in the accompanying drawings, in which:

Figure 1 is a sectional view showing a snap button of well known form applied to two pieces of cloth or two parts of a garment by means of wire in accordance with my invention. The section of Figure 1 is taken on line 1—1 of Figures 2 and 3.

Figure 2 is a top plan view showing part of the cloth removed from the fastener.

Figure 3 is a bottom plan view with part of the cloth removed.

Figure 4 shows a modified construction, the view being partly in plan and partly in section and with the cloth covering one part of the member, which in this instance is the socket member of the fastener.

Figure 5 is a detail sectional view on the line 5—5 of Figure 4.

Figure 6 is a detail sectional view on the line 6—6 of Figure 4.

Figure 7 is a bottom plan view of the stud member of the fastener applied to a piece of cloth.

Figure 8 is a detail view in section on the line 8—8 of Figure 7.

Figure 9 is a detail view in section on the line 9—9 of Figure 7.

The two pieces of cloth shown in the several figures are designated by the letters A and B. The socket member of the fastener is indicated by the letter C, and the stud member by the letter D. These two members are of well known construction.

The socket member is provided with a spring c. The inner ends of the spring are

adapted to enter through slots in the socket member in the usual way to engage the stud member. The outer ends of the spring are held by curled over portions d of the peripheral portion of the socket member. It will be observed that the socket member is not formed with thread holes, but a wire E is employed for attaching this member to the cloth. The peripheral part of the socket member has portions e turned inwards to form tubular parts, as clearly illustrated in the drawings. These parts are arranged suitable distances apart to provide spaces between them, and the wire E is passed through all of the parts e and across the spaces between these parts. The wire is applied to the socket member and to the cloth by devices which are applied to the socket member and to the cloth in such manner as to raise the cloth as indicated at F in Figure 2 between the parts e, while the remainder of the cloth is depressed below these parts as indicated at f. In this way alternate raised portions and depressed portions are formed and the wire is made to pass through and across these raised and depressed portions, and thus connect the member to the cloth.

The stud member is connected with the cloth in a substantially similar way. The base of the stud member is provided with tubular parts g extending from the periphery of the base inwards and arranged suitable distances apart to provide spaces h between them. By means of suitable devices the cloth is formed with raised portions i, while depressed portions k are left between the raised portions, and then by suitable devices the wire E' is inserted to connect the member to the cloth.

In Figures 4 and 7, I have shown a modified way of accomplishing the same results. In Figure 4 the socket member L is formed with peripheral projections l, which are tubular and are arranged suitable distances apart to provide open spaces l'. The wire E² is inserted in the manner before described, the only practical difference between what is shown in Figure 4 and what is shown in Figure 2 is that the tubular portions l are arranged outside the periphery instead of inside thereof. In Figure 7 the stud member D' is formed with tubular parts m to receive the wire E³, there being spaces or curved recesses n between the tubular parts m. The wire E³ is inserted

or applied to the cloth and to the fastener in the manner before described.

I claim as my invention:—

1. The combination with a piece of cloth 5 of a fastener, comprising a member provided with tubular projections with open spaces between them to receive portions of the cloth between said projections, and a wire which extends through the cloth and 10 through said projections.

2. A garment fastener comprising a member having in its peripheral portion tubular parts arranged suitable distances apart with

vacant spaces between them, and a flexible wire arranged in said tubular parts. 15

3. A garment fastener comprising a member having in its peripheral portion hollow tubular parts adapted to receive a wire when inserted endwise and which tubular parts are arranged suitable distances apart 20 to provide spaces to receive portions of the cloth to which the button is applied.

In testimony whereof, I have hereunto subscribed my name.

VOJTECH PUC.
